(57) **CLAIM**

The ornamental design for a draft inducer, as shown and described.

DESCRIPTION

FIG. 1 is a bottom perspective view of a draft inducer in accordance with the present invention.

FIG. 2 is another bottom perspective view thereof.

FIG. 3 is a top perspective view thereof.

FIG. 4 is another top perspective view thereof.

FIG. 5 is a side perspective view thereof.

FIG. 6 is a bottom plan view thereof.

FIG. 7 is a top plan view thereof.

FIG. 8 is a side elevation view thereof.

FIG. 9 is another side elevation view thereof.

FIG. 10 is another side elevation view thereof; and,

FIG. 11 is another side elevation view thereof.

All of the broken lines in the accompanying drawings illustrate environmental structure and form no part of the claimed design.
